CLAIM

The ornamental design for a combined eight conductor
modular plug and test adapter, substantially as shown
and described.

DESCRIPTION

FIG. 1 is a perspective view of the combined eight
conductor modular plug and test adapter showing my
new design;

FIG. 2 is a fragmentary top plan view thereof with the
plug portion being omitted for ease of illustration;

FIG. 3 is a sectional view thereof taken along line 3—3

of FIG. 2;

FIG. 4 is a sectional view thereof taken along line 4—4

of FIG. 2;

FIG. 5 is a bottom plan view thereof with the connect-

ing lead shown broken away for ease of illustration.
